(57) **CLAIM**

The ornamental design for an air compressor, as shown and described.

DESCRIPTION

FIG. 1 is a right front perspective view of an air compressor showing a first embodiment of my new design.

FIG. 2 is a right side view of FIG. 1

FIG. 3 is a left side view of FIG. 1

FIG. 4 is a rear view of FIG. 1.0

FIG. 5 is a front view of FIG. 1.

FIG. 6 is a top view of FIG. 1; and,

FIG. 7 is a bottom view of FIG. 1.

The dashed lines and the areas within the dashed lines form no part of the claimed ornamental design.
